DESIGN FOR A SCREW-CAP LOOSENER

Milton Morse, New York, N. Y.

Application March 6, 1946, Serial No. 127,167

Term of patent 14 years

(Cl. D44—29)

To all whom it may concern:

Be it known that I, Milton Morse, a citizen of the United States and a resident of New York City, county and State of New York, have invented a new, original, and ornamental Design for a Screw-Cap Loosener, of which the following is a specification, reference being had to the accompanying drawing, forming part thereof.

Figure 1 is a bottom plan view of a screw-cap loosener, showing my new design;

Figure 2 is an edge view thereof;

Figure 3 is a top plan view; and

Figure 4 is a cross-sectional view along the line 4—4 of Figure 3.

The dominant features of the design reside in the parts shown in full lines in the drawing.

I claim:

The ornamental design for a screw-cap loosener, substantially as shown and described.

MILTON MORSE.
